(57) **CLAIM**

We claim the ornamental design for an auger housing with
drift cutters for a snow thrower, as shown and described.

DESCRIPTION

FIG. 1 is a top front perspective view of an auger housing with
drift cutters for a snow thrower of the present invention;
FIG. 2 is another top front perspective view thereof;
FIG. 3 is a top rear perspective view thereof;
FIG. 4 is a first side view thereof;
FIG. 5 is a second side view thereof;
FIG. 6 is a front view thereof;
FIG. 7 is a rear view thereof;
FIG. 8 is a top view thereof; and,
FIG. 9 is a bottom view thereof.

The ornamental design which is claimed is shown in solid
lines in the drawings. Any broken lines in the drawings are for
illustrative purposes only and form no part of the claimed
design.

1 Claim, 9 Drawing Sheets
